DESIGN FOR A HANG-TYPE SMOKER'S PIPE

Kurt F. J. Kirsten, Seattle, Wash.

Application July 1, 1946, Serial No. 131,252

Term of patent 14 years

(Cl. D85—8)

To all whom it may concern:

Be it known that I, Kurt F. J. Kirsten, a citizen of the United States and a resident of Seattle, in the county of King and State of Washington, have invented a new, original, and ornamental Design for a Hang-Type Smoker's Pipe, of which the following is a specification, reference being had to the accompany drawing, forming a part thereof.

In said drawing:

I claim:

The ornamental design for a hang-type smoker's pipe, as shown.

KURT F. J. KIRSTEN.
